UNITED STATES PATENT OFFICE

CHARLES E. DE LONG, OF SAN DIEGO, CALIFORNIA, ASSIGNOR TO SANGAMO ELECTRIC COMPANY, OF SPRINGFIELD, ILLINOIS, A CORPORATION OF ILLINOIS

ELECTRICALLY-WOUND CLOCK

Original application filed October 4, 1926, Serial No. 139,293. Divided and this application filed June 2, 1927. Serial No. 195,880.

The present invention relates to electrically wound clocks, and is divisional of my copending application, Serial No. 139,293, filed October 4, 1926. More particularly the invention relates to clocks wherein the energy for winding the main spring is derived from a small electric motor, generally incorporated in the clock.

Heretofore, in clocks of this type, the customary method of controlling the motor, i. e., stopping and starting the same with the winding and unwinding of the clock spring, has been to open and close the motor circuit, through switch mechanism made responsive to the tension of the main spring, or actuated by the winding and unwinding of the spring through a predetermined number of turns. Electrical contact requiring frequent opening and closing are always subject to pitting, arcing, etc., and hence these prior clocks have not been commercially successful, owing to the imperative necessity of a clock giving reliability of operation over indefinite periods of time, without service or attention.

The fundamental object of the present invention is to obviate the difficulties inherent in the use of electrical contacts by providing an electrically wound clock in which the control exercised over the motor is in the nature of a mechanical braking thereof rather than an opening and closing of the motor circuit. Small motors of the induction type are now obtainable, which will permit of braking down to a dead stall without injury to the motor and without any objectionable load fluctuation being imposed on the line supplying the motor. Such motors can be slowed down, stopped and started indefinitely through braking retardation without deterioration of any of the working parts of the clock mechanism or motor.

A further object of the invention is to provide improved braking mechanism which will be sensitive in its action, to the end of keeping the winding and unwinding limits of the clock spring within a comparatively small range, whereby an approximately uniform tension is always maintained on the clock spring. The braking control forming

the essence of this invention enables this tensional variation of the clock spring to be maintained between much closer limits than is practicable in a clock wherein the motor circuit is opened and closed by contact mechanism. Because of the pitting and deterioration of the contacts in these latter types of electrically wound clocks it is not practicable to open and close the motor circuit with the frequency required to obtain this close regulation of the clock spring tension. Such close regulation of the clock spring tension, as obtained by the present braking control, augments the time keeping accuracy of the clock.

Referring to the accompanying drawing illustrating a preferred embodiment of my invention:

Fig. 1 is a front or face view of a clock movement embodying the invention, the front mounting plate being broken away to illustrate part of the gear train;

Fig. 2 is a transverse sectional view taken on the plane of the line 2-2 of Figure 1, the major part of the gear train being omitted from this figure for clarity of illustration;

Fig. 3 is an axial sectional view of the threaded countershaft and cooperating threaded gear, and

Fig. 4 is a fragmentary detail view of the two cooperating braking elements.

The clock movement may be of any preferred design or construction, the present invention being capable of embodiment in practically any type of movement with very little modification of standard construction. As exemplary of a typical construction of clock, I have shown in Figs. 1 and 2 a design wherein the gear train, main spring, etc., are all mounted in a frame structure comprising front and rear disc-like plates 8 and 9, held in spaced relation by posts 11. The minute hand (not shown) is carried on a central arbor 12, and the hour hand is supported on a sleeve 13 which is connected to the minute hand arbor through the usual speed reducing gearing 14, as is typical of conventional clock construction. The electric motor 15, which winds the main spring,

is preferably mounted on the outer side of the rear plate 9, the frame of the motor having extending lugs 17 which are secured to spacing posts 18 by screws 19. This motor is preferably of a small induction type, capable of being connected directly to an ordinary lighting circuit. The armature shaft 21 of the motor extends through the back plate 9 and carries a small pinion 22 which meshes with a relatively large gear 23 on an arbor 24 pivoted between the end plates. The pinion 22 and gear 23 are preferably located in close proximity to the back wall 9, the large gear 23 constituting the rotating element to which the braking retardation is applied, as will hereinafter appear.

The reduced speed of the arbor 24 is transmitted through a pinion 25, mounted on this arbor, to a large gear 26 mounted on a second arbor 27, also journaled in the end plates 8 and 9. A pinion 28 mounted on this second arbor transmits the reduced speed thereof to a large gear 29 mounted on a third arbor 31, also journaled at its ends in the front and rear plates. On this third arbor is a pinion 32 which meshes with a large gear 33 which is pinned to the main spring arbor 34. The second and third arbors 27 and 31, together with their respective gears, have been omitted from Fig. 2 to avoid obscuring the illustration of the braking mechanism. As shown in this figure, the main spring 35 and spring barrel 36 are mounted on the main spring arbor 34, preferably adjacent the back plate 9, the spring barrel being freely rotatable on the arbor. The inner convolution of the main spring 35 is suitably secured to the arbor 34, as by the pin 37. The outermost convolution of the main spring is suitably connected to the spring barrel, whereby the tension of the spring operates to rotate the spring barrel, and the ring gear 39 extending from the periphery thereof. This ring gear 39 meshes with a pinion 41 mounted on the central, minute hand arbor 12. Any suitable escapement mechanism 42 is operatively connected to the minute hand arbor 12 through a suitable gear train, not shown.

Extending substantially parallel to the main spring arbor 34 is a countershaft 44 which has its ends suitably journaled in the front and rear plates 8 and 9. Formed on this countershaft is an enlarged threaded portion 45 over which screws an internally threaded gear 46 which has a relatively wide toothed periphery for meshing with the gear 33 of the main spring arbor 34. A second gear 47, which is rigidly pinned or keyed to the countershaft 44, meshes with the ring gear 39 of the main spring barrel. Extending from one side of the relatively wide gear 46 is a grooved collar 48 which is embraced by the forked end 49' of a brak-

ing lever 49. Such lever extends transversely through the various parts of the gear train above described (Fig. 1) for pivotal mounting at 50 on a post 51 extending forwardly from the back wall 9 at a point adjacent to the gear 23 and arbor 24. The pivotal mounting of the lever 49 on the post 51 is preferably effected by forking this end of the lever to embrace the post and to receive the pivot pin 50 passing through the lever and post. Adjacent to its pivoted end, the lever carries an adjustable screw member 53 having a threaded portion 54 screwing through a tapped hole in the lever. The inner end of this screw is adapted to bear against a braking surface 55 rotating with the gear 23. This braking surface 55 may be the actual side of the gear, but preferably it consists of a disk of fibre or some similar material secured to the gear.

In the operation of the clock, the energization of the motor 15 will drive through the gear train previously described, which will operate to impart a slow speed winding rotation to the main spring arbor 34. As the driving gear 33 of this arbor is revolving, it is also revolving the relatively wide countershaft gear 46, with which it is in continuous mesh. With tension existing in the spring 35 the spring barrel 36 will, of course, also be rotating in the same direction as the arbor 34, but the rotation of this spring barrel will be so slow compared to the winding rotation of the arbor that it may be considered as practically stationary. Hence the gear 47 and threaded portion 45 of the countershaft 44 will remain almost stationary, with the result that the appreciably higher speed of rotation of the gear 46 on the countershaft will cause this gear to screw inwardly towards the back plate, the thread 45 having this direction of lead. As the spring approaches the desired limit of its winding tension the grooved collar 48 will gradually swing the braking lever 49 backwardly. This will bring the end of the screw member 53 against the braking face 55 on the gear 23, exerting a gradual braking retardation thereon, until the motor 15 ceases, or substantially ceases rotation, at the point where the desired winding tension has been given the spring 35.

With the main spring arbor 34 inert, or substantially inert, as the result of the aforesaid braking action, the continued rotation of the spring barrel 36, and hence of the countershaft 44 will gradually screw the wide gear 46, which is now held against rotation, backwardly along the thread 45 towards the front plate 8. When the spring barrel has revolved through a given angular distance, corresponding to the lower predetermined limit of its spring tension, the gear 46 will have moved backwardly along the countershaft 44 to the point where the

braking friction of the screw member 53 will be removed from the brake surface 55. Thereupon the motor 15 will be permitted to resume rotation, with the result that the main spring will again be wound to a predetermined tension through a repetition of the cycle previously described.

In the event of the supply of current to the motor being interrupted, the reserve tension of the main spring 35 will be sufficient to continue the operation of the clock for a considerable period of time. As soon as current again comes back on the line the motor will rewind the main spring to its previous working tension. By adjusting the screw 53 in its threaded mounting in the lever 48, the upper limit of the working spring tension can be shifted to any desired point in the total range of spring tension.

20 What I claim as my invention and desire to secure by Letters Patent, is—

1. In a device of the class described comprising a spring, a spring barrel and an electric motor for winding said spring, the combination of two cooperating threaded members disposed eccentrically of said spring barrel and cooperatively connected to the opposite ends of said spring, and brake mechanism responsive to predetermined relative movement between said threaded members for applying a gradual braking retardation to said electric motor.

2. In mechanism for winding a spring motor comprising the spring, an arbor and an electric motor for winding said spring, the combination of a countershaft disposed eccentrically of said arbor, two cooperating threaded members on said countershaft, means rotatably connecting said threaded members with the opposite ends of said spring, brake mechanism responsive to predetermined relative movement between said threaded members for applying a gradual braking retardation to said electric motor, and means for adjusting said brake mechanism.

3. In mechanism for winding a spring motor comprising the spring, and an electric motor for winding said spring, the combination of a pair of cooperating screw threaded members having geared connection with the opposite ends of said spring to be revolved thereby, and lever actuated brake means responsive to predetermined relative movement between said members for applying a gradual braking retardation to said motor.

4. In mechanism for winding a spring motor comprising the spring, an arbor therefor, a spring barrel, and an electric motor for winding said spring, the combination of a pair of interacting relatively movable members, gear means for driving one of said members from said arbor, gear means for driving the other of said members from said spring barrel, a lever having stationary piv-

otal mounting adapted to be swung by relative movement between said members, and brake mechanism responsive to said lever for applying a gradual braking retardation to said electric motor.

5. In mechanism for winding a spring motor comprising the spring, an arbor therefor, a spring barrel, an electric motor and a gear train operatively connecting said electric motor with said spring, the combination of a rotating brake surface associated with said gear train adjacent to the motor end thereof, a gear rotating with said arbor, a gear rotating with said spring barrel, a countershaft driven by one of said gears, a thread on said countershaft, a gear screwing over said thread and driven by the other of said gears, a lever responsive to relative axial movement between said countershaft and said gear mounted thereon, and a screw member having adjustable threaded mounting in said lever for applying gradual braking pressure to said brake surface.

6. In mechanism for winding a spring motor comprising the spring, an arbor therefor, a spring barrel, an electric motor and a gear train operatively connecting said electric motor with said spring, the combination of a rotating brake surface adjacent to the motor end of said gear train, a countershaft comprising a threaded portion, means for driving said countershaft from said barrel, an internally threaded gear screwing over the threaded portion of said countershaft, means for driving said latter gear from said arbor, a collar on said latter gear, a lever having a forked end embracing said collar and arranged to be swung by the axial movement of said threaded gear along said countershaft, and a pin having adjustable threaded mounting in said lever and actuated thereby for engaging with said brake surface.

7. In mechanism for winding a spring motor, the combination of the spring, an arbor therefor, a spring barrel, an electric motor, a pinion on the armature shaft of said motor, a spur gear driven by said pinion, a rotating brake surface mounted on one side of said spur gear, a gear train driven through said spur gear and operatively connected with said spring, a gear rotating with said arbor, a gear rotating with said spring barrel, a countershaft driven by one of said latter gears, a thread on said countershaft, a gear screwing over said thread and driven by the other of said latter gears, a lever responsive to relative axial movement between said countershaft and said gear mounted thereon, and means actuated by said lever for applying gradual braking pressure to said rotating brake surface, to stop said electric motor by stalling the same.

8. In mechanism for winding a spring
